UNITED STATES PATENT OFFICE.

CHARLES P. WATSON, OF PHILADELPHIA, PENNSYLVANIA, ASSIGNOR TO THE WATSON ARMS COMPANY, A CORPORATION OF DELAWARE.

DETONATOR FOR ORDNANCE-PROJECTILES.

1,197,414.

Specification of Letters Patent. Patented Sept. 5, 1916.

Application filed November 21, 1914. Serial No. 873,220.

To all whom it may concern:

Be it known that I, CHARLES P. WATSON, a citizen of the United States, residing at Philadelphia, in the county of Philadelphia and State of Pennsylvania, have invented certain new and useful Improvements in Detonators for Ordnance-Projectiles, of which the following is a specification.

10 My invention relates to a detonator for ordnance projectiles.

It has been devised with especial reference to use in connection with projectiles loaded with high explosives and has for its 15 object to render the detonator certain in its operation and also absolutely safe, that is to say, it is of such construction and arrangement that it cannot possibly be armed except by the firing of the shell from the 20 gun, and at the same time it will positively prevent the explosive charge within the shell from being ignited or detonated should, through any unforeseen circumstance, the priming charge of the detonator 25 or any part thereof detonate or explode. These objects are successfully attained by the use of my invention.

In the accompanying drawings I have 30 illustrated the preferred form of such invention, without however wishing by such delineation to restrict myself to the arrangement and detail shown, as that may be modified or changed without departing 35 from the principle of the invention.

35 In such drawings, Figure 1 is a central longitudinal section of a detonator embodying my invention; Fig. 2 is a transverse sectional view taken on the line II—II of Fig. 1; Figs. 3 and 4 are sectional views 40 both taken on the line III—III of Fig. 1 but viewed respectively from different directions. Fig. 5 is a detail view in elevation of the plunger that carries the firing pin, and the associated parts that operate 45 it, such pin being represented in the armed or firing position; Fig. 6 is a longitudinal sectional view of the parts represented in Fig. 5 in the position they there occupy. Fig. 7 is a view similar to Fig. 6 except that 50 the parts are represented as in normal position, that is, with the firing pin retracted and in inoperative position; Fig. 8 is a transverse sectional view taken on the line VIII—VIII of Fig. 5; Fig. 9 is a transverse 55 sectional view similar to Fig. 8 except that the

parts are represented in the normal inactive position represented in Fig. 7. Fig. 10 is a detail view in perspective illustrating one of the centrifugally-acting bodies employed to control the positions of the firing pin; Fig. 60 11 is a detail longitudinal sectional view of the support for the primer, the miniature projectile that contains a detonating charge of high explosive and the charge of powder that propels said miniature projectile; Fig. 65 12 is a view in central longitudinal section showing one way of mounting the firing pin for the miniature projectile carrying the detonating charge of sensitive explosive different from that shown in Fig. 1. 70 Fig. 13 is a transverse section taken on the line XIII—XIII of Fig. 1.

In the drawings 2 indicates the body of the detonator. It is preferably in the form of a steel plug of high tensile strength 75 adapted to be screwed into the breech of a shell, and bored out to form a central chamber open at its forward end. The rear portion of this chamber is smooth and contains a ponderous body, in the form of a plunger 80 3, that fits this part of the chamber quite closely and is free to move therein longitudinally to a limited extent.

5 indicates a spring interposed between the rear end of the plunger and the body of the detonator and acting to normally hold the plunger in its forwardmost position. While this spring is not essential to my invention I prefer to use it, as it holds the plunger quite firmly in the position represented in Fig. 1, and prevents it from moving as the shell is being handled, and though such movement would be attended with no danger it might awaken suspicion on the part of one handling a shell equipped with my detonator who was uninformed as to its construction. There is formed through the body of the plunger 3 a transverse angular opening, 4, with which communicates a centrally disposed perforation 6 in which is 85 loosely mounted the stem of the firing pin 7. This pin has a head 8 with inclined peripheral edges, and with a shallow recess 10 in its rear face, for a purpose to be described later. Its stem is of a length greater than the length of the perforation 6, so that when moved forward the tapering or pointed end thereof projects beyond the front face of the plunger 3, and when retracted such point lies within the body of the plunger and the 90 105 110

head 8 extends well within the transverse opening 4. A coiled spring 9 surrounds the stem of the firing pin and is located between its head and the body of the plunger, and 5 operates to retract the pin so that its point or firing end is entirely within the aperture 6 and back of the front face of the plunger. Fitting within the transverse opening 4 in the plunger are two centrifugally acting, 0 counterpart, bodies 11, 11, each provided with a locking and wedge member 12. Each wedge member 12 is relatively thin, and the two are adapted to overlap and lie alongside of each other face to face when the 5 bodies 11 are moved inward as indicated in Figs. 7 and 9, and to slide over each other as the said bodies move outward to the positions indicated in Figs. 5, 6 and 8. Each member 12 is formed with a locking shoulder 13 that is adapted to overlie the head of the firing pin and hold it retracted when the parts are in inactive, normal position, Figs. 7 and 9; and also with an inclined wedge part 14, that engages with the inclined edge of 5 the head of the pin and, in coöperation with its like companion member, operates to force the firing pin outward into armed position, when the bodies 11 are thrown outward by centrifugal force. As has been stated, the 0 spring 9 tends to move the firing pin inward into the body of the plunger, and such spring hence operates, through the engagement of the inclined faces of the head of the pin with the inclined edges of the wedge 5 portions 14 of the centrifugally operating members 11, to move the latter inward to a central position, with the flat base parts 15 of said bodies directly back of and in engagement with the inner face of the firing 0 pin head.

It is conceivable that a loaded shell might be subjected to a force that would tend to move one of the bodies 11 outward, as for instance should it fall upon its side; but this 5 would not arm the detonator, for the reason that the locking shoulder 13 of the opposite body 11 would prevent the outward movement of the pin. It requires the simultaneous and conjoint action of the two wedge 0 parts 14, acting upon the head of the firing pin, to move it forward, against the action of the spring 9, and into armed position, and this can only take place when the detonator is subjected to rapid rotation. This 5 latter occurs only, after the detonator has been applied to a shell, when the shell is fired from a gun, and hence no circumstances incident to the ordinary handling of the shell, or any accidents to which it might be 0 subjected can possibly arm the firing pin of the detonator. When, however, the shell is fired and begins to rotate, the two bodies 11 simultaneously move outward and separate the wedge faces 14, which act upon the head 5 of the firing pin from opposite sides and

project it forward, against the force of the spring 9; and at the same time the shoulders 13 are withdrawn from over the head 8 leaving the firing pin free to be moved forward. By the time the bodies 11 reach the limits of 70 their outward movements their faces come into engagement with the inner wall of the detonator body by which they are arrested, when the ends of the wedge parts 14 are brought together under the center of the 75 head of the firing pin and enter the recess 10 formed therein, the spring setting back the firing pin to cause this. The edges of the recess, and the ends of the wedges 14, are so shaped that when they come together 80 as just mentioned the head of the firing pin forms a lock that holds the bodies 11 outward the spring 9 insuring constant engagement between said locking parts. This is desirable for two reasons: The parts 14 of 85 the centrifugally acting bodies constitute a solid abutment behind the firing pin and between it and the heavy plunger 3 as soon as the pin comes into armed position and the lock aforesaid insures that this solid 90 abutment shall be maintained even though centrifugal force should be largely reduced by the slowing down of the speed of rotation of the shell during its flight.

42, 42 indicate small pins or studs extending from the outer faces of the bodies 11 and adapted to enter a circumferential recess 43 formed in the inner wall of the detonator body when the plunger has been fully set back. This set back of the plunger takes 100 place, as is well understood, when the gun is discharged. The pins operate to positively hold the plunger from creeping forward after acceleration in the flight of the shell has ceased. They are of such size that 105 they are sheared off at the moment of impact of the shell, then allowing the plunger to move forward relative to the detonator body, the spring 5 assisting in causing such forward movement. They may be formed integral with the bodies 11, or of lead or some other soft material secured to such bodies. These pins serve not only to hold the plunger in its set back position as has been described, but, if properly proportioned in length to 110 the other parts of the apparatus with which they are associated, they may also serve to prevent the bodies 11, or either of them, from being moved outward sufficiently far to unlock the firing pin except when the plunger 115 is set back, thus adding another element of safety to the device, since the conjoint setting back of the plunger and outward movements of the centrifugally acting bodies 11 can take place only under conditions set up 120 when the shell is fired from a gun.

The shear pins 42 constitute means that are brought into operation during the flight of the shell for positively holding the plunger in a fixed position with reference to 130

the primer 17 until impact with the objective of the shell takes place. This has been found an important feature, since it tends to fix the duration of one of the time elements that enter into the delay in detonation after impact; for by positively fixing the position the plunger shall occupy with reference to the primer at the moment of impact, the distance the plunger has to travel before the primer is engaged and fired is positively determined, and this distance may be greater or less, within the limits of movement of the plunger, accordingly as a quicker or more delayed firing of the primer after impact may be desired. Where means for thus fixing the position to be occupied by the plunger upon impact are not provided, the position of the latter becomes an uncertain factor, it sometimes being close to the primer and sometimes farther from it, and hence an element of uncertainty is introduced, thus making it more difficult to determine the moment of detonation of the projectile than when using an arrangement such as I show and have just described.

Since the plunger fits the walls of the chamber in which it is mounted quite closely I find it desirable to form longitudinal air channels in it in order to permit air to circulate as it moves from one end of its travel to the other. The air passages may be grooves 50 in the surface of the plunger, or longitudinal perforations through the body of the plunger.

There is supported within the body of the detonator and directly in front of the plunger 3 a plug or support in which is mounted the primer and the detonating capsule or miniature projectile containing a small charge of high explosive. The support, represented in detail in Fig. 11, is designated 16 and is preferably screwed into the body 2 as indicated in Fig. 1. It is provided with a seat for the cap or primer 17 and with a chamber 18, communicating through a small hole or flash passage 19 with the recess in which is seated the cap 17. In the rear portion of this chamber is placed a charge of black powder, indicated at 49, and directly in front of this is a capsule or miniature shell 20 containing a high explosive, such as fulminate of mercury. A wad 21 preferably separates the charge of black powder from the base of the capsule 20. The latter is preferably formed of a steel shell with a removable head 22 secured to and closing the front open end thereof, through which the shell is charged. This head is perforated and formed with a seat for a detonating cap 23.

The booster charge, the detonation of which ruptures the detonator and fires the main charge of the shell, is located in the portion 24 of the chamber at the forward end of the detonator body. The booster

charge should be of an explosive material that is relatively highly resistant to shock and heat, and tri-nitrotoluol is such a substance. This chamber 24 is separated from the rest of the detonator chamber by a plug 70 25, screwed into the body 2, and centrally perforated, at 26, in line with the capsule 20. The inner end of the passage 26 is closed by a valve device 27. I prefer that this valve shall be formed as a projection 75 carefully ground to fit its seat at the end of passage 26, and carried by or formed integral with a plate 28 pivoted to the forward face of a sliding valve carrier 29. This latter is perforated at 30, also in line with the 80 capsule 20 and the perforation 26. It is normally held in a forward position with the valve 27 seated, by a coiled spring 31 interposed between the valve carrier and the plug 16. The latter is preferably formed 85 with a forwardly projecting reduced portion 32 around which the spring 31 is coiled and constituting the seat for the capsule 20. The valve and its supporting plate are eccentrically pivoted at 33 to the outer face of the 90 valve carrier, and are acted upon by a spring 34 that normally holds the plate against a stop pin 35 with the valve in position to close the passage 26.

36 indicates a shallow seat formed in the 95 inner face of the plug 25 concentric with the opening 26, into which the face of the valve 27 sets when thrown outward by centrifugal force to uncover the opening 26, as will be described.

38 is a plate screwed into the inner open end of the detonator body and closing the chamber 24 that incloses the detonating booster charge. It carries a firing pin 39 that is directly in front of and in line with the capsule or small projectile 20, and is arranged to act through the central perforation in the head thereof upon the cap 23. Between the plug 25 and the plate 38, and in line with the openings 26 and 30 is a 105 corrugated tube 37 through which the projectile or capsule 20 passes in its flight toward its firing pin 39. This tube is hermetically sealed at its ends in the supports in which it is mounted and serves to separate the passage for the capsule 20 from the charge of explosive within the chamber 24, and, being corrugated, forms air passages for venting the tube as the said projectile enters and passes through it.

Instead of supporting the pin 39 that fires the charge of the miniature projectile 20 rigidly as has been described, it may be loosely mounted within the corrugated tube 37 and supported upon a spring 51, interposed between the base of the pin and the plate 38, as represented in Fig. 12. With this arrangement the spring 51 holds the firing pin 39 normally near the inner end of the tube 37. But upon impact of the 110 115 120 125 130

shell the pin jumps forward, compressing the spring. Upon slight impact, as when striking thin armor, the distance that this firing pin moves forward and the amount it compresses the spring will be less than the distance it moves when the impact is more severe, as when heavy armor is struck, and this feature of operation may be utilized to automatically govern the time of exploding the shell after impact; for, as will be seen, the firing pin is less distant from the seat of the miniature projectile when light armor is struck, than it is when heavy armor is encountered, and hence the said miniature projectile has to travel a greater distance before it is detonated in the latter case than in the former. The time it takes in traveling this greater distance can be made to correspond with the difference between the time taken by the shell to penetrate light armor and heavy armor. The same result as that just described may be accomplished by means of an air spring in place of the metallic spring 51 illustrated in the drawings.

40 indicates a pointed pin of hard tool steel set into the rear end of the plunger 3 and projecting rearward.

The supporting plug 16 is provided with one or more longitudinal through pas-

35 sages 41.

With this description of the detail construction of the detonator, a general statement of its advantages and method of operation may be given. Fig. 1 represents the device with its parts in normal position, that is, unarmed. It will be seen that the firing pin 7 is retracted so that it cannot possibly be brought into engagement with the cap 17 and that no manipulation of the 40 shell nor any movement thereof except such movements as are imparted to it in the act of being fired from a gun can possibly arm the detonator and set the firing pin in position to act upon the said cap. It will also be seen that the passage between the chamber in which is situated the plug 16 and where are located the detonating capsule 20, the charge of powder 19 that propels it, and the primer caps 17 and 23,—all explosives 45 sensitive to shock or heat, or both—is cut off from the chamber 24 containing the booster charge, which is not sensitive to shock or heat, by a gas-tight valve, so that should the said sensitive explosives, or any 50 of them, through any cause whatever detonate or explode, the same and gases and incident detonating waves from them cannot possibly reach the chamber 24 containing the booster charge of high explosive.

55 It will also be observed that the passages 41 through the plug 16 permit the gases which would be generated by a premature detonation of the charge of the capsule 20 to pass to the rear of the said plug, as well as to 60 fill the chamber directly in front thereof,

so that the pressure of these gases is instantly very much reduced through expansion, as well as by being robbed of their heat by the surrounding metal. The great pressure that would be exerted in the chamber in which is located the plug 16 by such premature explosion would operate to press forward the valve carrier 29, and force the valve more tightly into its seat, thus increasing its effectiveness in preventing the 70 passage of any of the said gases beyond said valve and into the tube 37. If there should be some slight passage of gas beyond the valve it would do no harm, since the tube 37 would prevent its direct action upon the charge within the chamber 24, the tube being, as stated, hermetically sealed at each 75 end in its supports.

Upon a shell carrying a detonator such as that described being fired from a gun the 80 plunger 3 is violently set back, compressing the spring 4 and forcing the hard steel point 40 into the softer metal of the body. The plunger will move back until the pins 42 carried by the centrifugally-operating 85 bodies 11 come opposite to the groove 43 formed in the detonator body. At the same time the valve carrier or plunger 29 moves toward the rear, compressing the spring 31 and freeing the valve 27 from its seat. The 90 rotary motion given to the shell by the rifling of the gun is positively communicated to the plunger 3 by reason of the pin 40 being embedded somewhat in the body of the detonator; while rotation is imparted 95 to the valve carrier 29 because of the frictional engagement it has with the inner walls of the detonator body and the compression of the spring 31. The centrifugal force generated by the rotation of the shell 100 acts to simultaneously move outward the two bodies 11, forcing forward and into armed position the firing pin 7 where it is held during the flight of the shell. Centrifugal force also acting upon the valve 27 105 causes it to swing from the position indicated in full lines in Fig. 4, to that indicated in dotted lines, when, it will be seen, the spring 34 lies nearly across the pivot 33, and hence exerts very little force tending to 110 restore the valve to its central position. As soon as the acceleration of the shell has ceased the spring 31 moves the valve carrier forward until the face of the valve comes into engagement with the groove 26 in the 115 inner face of the plug 25, where it will become seated and be held, by centrifugal force and the spring 31, out of the line of flight of the detonating capsule or projectile 20, in front of which is now a free pas- 120 125 130

sage between it and its firing pin 39. Upon impact of the shell the plunger 3 jumps forward, shearing off the pins 42 which have until then held it retracted, and the firing pin strikes the cap 17, exploding it. This ignites the charge of black powder 19 which operates to propel the small projectile 20 carrying the detonating charge forward through the perforations 30, and 26 and the tube 37. Upon reaching the firing pin 39, the cap 23 is exploded, the detonation of the charge within the capsule 20 takes place, and this in turn detonates the booster charge in the chamber 24, rupturing the detonator and firing the charge within the shell.

It will be seen that the firing of the shell is by a stepping-up process accomplished by a succession of explosions or minor detonations, and that although these successive explosions follow one another rapidly, an appreciable length of time occurs between impact of the shell and the final detonation of the shell charge, constituting a delay action. First, upon impact, the plunger has to travel forward until the firing pin acts upon the cap or primer 17, then this has to ignite the charge of powder 19 that propels the capsule or shell containing the detonating charge, this has to travel from the position it normally occupies to the end of the tube 37, and then be exploded, and finally the effects of its explosion have to be communicated to and detonate the booster charge and this in turn rupture the detonator and set off the charge within the shell. This retarding of the detonation of the shell is utilized to accurately determine the length of time after impact when the shell shall burst, because by varying the amount of the powder charge, 19, the speed at which the miniature projectile moves toward the firing pin 39 may be governed and hence the length of time after impact when the charge within the capsule shall be fired.

It is to be understood that the capsule fits within its holder quite snugly so that the impact of the shell even when piercing heavy armor will not dislodge it, its propulsion being caused entirely by the charge of powder at 19.

In order that the flight of the projectile may be observed I provide the fuse with a tracer located in its rear end. For this purpose I form a chamber 44 in the rear end of the detonator body into which is packed the tracer compound. This is compressed into the chamber at a comparatively low pressure, thus making unnecessary the use of expensive high power compressing machinery. The outer end of the chamber 44 is tightly closed by a plate 45. This plate is perforated at 46, and such perforation is filled with fusible metal. Between the plate 45 and the charge 47 of tracer compound is

a small charge 48 of black powder. Upon the gun being fired the tremendous pressure exerted within the gun forces forward the plate 45 compressing the charge 47 to a degree not practicable by the use of any machinery of which I have knowledge. This compression takes place practically instantaneously, and immediately thereafter the plug filling the aperture 46 is melted and the charge of powder ignited. The combustion of this powder charge operates both to blow out the plate 45 and to ignite the tracer compound, this taking place after the shell has left the muzzle of the gun. The tracer compound now burns slowly and uniformly due to the density imparted to it in the manner just described.

What I claim is:—

1. In a detonator for projectiles, the combination of a detonator body, a longitudinally movable firing pin, a support within the said body in which the firing pin is mounted, and into the body of which the pin may be longitudinally retracted, and means for projecting the pin longitudinally on right lines, and beyond the face of the body in which it is supported when said means are acted upon by centrifugal force.

2. In a detonator for projectiles, the combination of a detonator body, a plunger slidable therein, a longitudinally movable firing pin carried by the plunger and arranged to be retracted into the body thereof, and means for projecting the firing pin beyond the surface of the plunger when acted upon by centrifugal force.

3. In a detonator for projectiles, the combination of a detonator body, a plunger slidable therein, a longitudinally movable firing pin carried by the plunger and arranged to be retracted into the body thereof, and centrifugally operated devices arranged within the said plunger and acting upon the firing pin for projecting it longitudinally beyond the surface of the plunger when acted upon by centrifugal force.

4. In a detonator for projectiles, the combination of a detonator body, a longitudinally movable firing pin, a support within the said body in which the firing pin is mounted, and into the body of which the pin may be longitudinally retracted, and means for projecting the pin longitudinally and beyond the face of the body in which it is supported when acted upon by centrifugal force, the said means being constructed also to lock the pin retracted under normal conditions.

5. In a detonator for projectiles, the combination of a detonator body, a firing pin, a support within the said body in which the firing pin is mounted and into the body of which the pin may be longitudinally retracted, and a plurality of radially sliding devices acting upon the said pin for pro-

jecting it longitudinally beyond the face of the body in which it is supported when acted upon by centrifugal force, each of the said devices being arranged to lock the pin retracted when in normal position but release it when moved by centrifugal force, whereby simultaneous movement of all the said devices is necessary to release the firing pin.

6. In a detonator for projectiles, the combination of a detonator body, a firing pin, a support within the body in which the said pin is mounted and into the body of which it may be longitudinally retracted, a spring tending to move the pin within the said body in its support, and means for projecting the pin longitudinally and against the action of the said spring into armed position when such means are acted upon by centrifugal force.

7. In a detonator for projectiles, the combination of a detonator body, a plunger slidable therein, in which is formed a transverse opening and also a central longitudinal perforation, a longitudinally sliding firing pin seated in the said perforation, radially sliding bodies mounted in the said transverse opening arranged to act upon the said pin and project it into armed position when they are acted upon by centrifugal force.

8. In a detonator for projectiles, the combination of a detonator body, a plunger slideable therein, in which is formed a transverse opening and a central longitudinal perforation, a longitudinally movable firing pin seated in the said perforation, radially sliding bodies mounted in the said transverse opening arranged to act upon the said pin and project it into armed position when they are acted upon by centrifugal force, each of the said bodies being provided with means for locking the pin in retracted position under normal conditions.

9. The combination in a percussion fuse of an anvil block and a hammer block movable the one with respect to the other longitudinally of the structure, a firing pin movable longitudinally in the said hammer block from an unarmed to armed position, and centrifugally operated means for shifting said firing pin from unarmed position toward said anvil.

10. The combination in a percussion fuse of a supporting body, a firing-pin movable in said body from an unarmed to armed position, and a pair of oppositely arranged centrifugally-operating slides each provided with an inclined firing-pin-impelling surface and with a transverse firing-pin-supporting surface.

11. In a detonator for ordnance shells containing a booster charge of high explosive, a miniature projectile containing a detonating charge for firing the booster charge normally supported within the detonator at a

distance from the booster charge, a charge of powder for propelling the miniature projectile into proximity to the booster charge, means operating upon impact of the shell for igniting the said powder charge, means for detonating the said miniature projectile upon the termination of its flight and in proximity to the booster charge, and a valve for closing gas-tight and against the flight of the said miniature projectile the chamber in which is located the said miniature projectile the valve being arranged to open the passage upon the firing of the shell from a piece of ordnance.

12. In a detonator for ordnance shells, a detonator body formed with two chambers in one of which is located a booster charge of explosive, and in the other of which, at a distance from the first mentioned chamber, is normally supported a miniature projectile carrying a detonating charge for setting off the booster charge, a strong partition separating the chambers in which the said charges are respectively normally located, there being a communicating passage between the chambers through the said partition, a valve closing said passage gas-tight, means for causing the valve to open upon the discharge of the shell from the gun, a charge of powder for propelling the miniature projectile from its normal position, through the said passage, into the chamber containing the booster charge and means operating upon impact of the shell for igniting the said powder charge to cause it to project the miniature projectile with its detonating charge into proximity to the booster charge and there causing it to detonate.

13. In a detonator for ordnance shells, a detonator body having a chamber for a booster charge and another chamber for a charge of an explosive of sensitive character for igniting the booster charge, and a strong partition separating the said chambers through which is a communicating passage uniting the chambers, a valve for closing the said passage gas-tight, a movable sliding carrier for the valve arranged to be set back and free the valve upon the shell being fired from the gun, the valve being arranged to be moved by centrifugal force out of position to close the said passage, and means for firing the said charges upon impact of the shell.

14. In a detonator, a case or body having a chamber for a booster charge of non-sensitive high explosive and another chamber remote therefrom containing a detonating charge of sensitive explosive for detonating the booster charge, the said chambers being separated by a strong partition through which is a passage uniting said chambers, a valve for closing said passage gas-tight, the valve being arranged to be moved to uncover the passage when the shell to which the det-

detonator is applied is fired from a gun, and a sliding carrier for the valve located in that chamber in which is the sensitive detonating charge movable in the detonator body 5 and normally held in position to seat the valve, whereby should the sensitive explosive accidentally explode or detonate, the pressure of gases caused thereby will act upon the said valve carrier and more tightly 10 seat the valve.

15. In a detonator for ordnance shells, a detonator body inclosing a chamber for a booster charge, and another chamber separated therefrom by a strong partition 15 through which is a passage uniting the said chambers, a plug secured in the second chamber adapted to support a miniature projectile containing a sensitive high explosive, a charge of powder for propelling the 20 said miniature projectile from its seat through the said passage into the chamber of the booster charge, and a primer for igniting said powder charge, and a plunger in rear of the said plug carrying a firing 25 pin, and means for arming the firing pin by centrifugal action at the instant the shell is fired from the gun.

16. In a detonator for ordnance shells, a detonator body inclosing a chamber for a booster charge and another chamber separated therefrom by a strong partition through which is a passage uniting the said chambers, a plug secured in the second chamber adapted to support a miniature projectile containing a sensitive high explosive, a charge of powder for propelling the said miniature projectile from its seat through the said passage into the chamber of the booster charge and a primer for igniting the 35 said powder charge, a plunger in rear of the said plug carrying a firing pin, means for arming the firing pin by centrifugal action at the instant the shell is fired from the gun, and a valve for normally closing the passage 40 between the said chambers gas-tight arranged to be moved to uncover the said passage when the shell is fired from a gun, the said plug having formed in it longitudinally 45 through perforations whereby the parts of the chamber in which it is situated on opposite sides of the plug are in communication 50 to permit expansion of the gases should there be a premature explosion or detonation of the sensitive explosive in such chamber.

17. In a detonator for ordnance shells, a detonator body having a chamber for a booster charge of high explosive near its front end, a strong partition cutting off said chamber from the interior of the rest of the 55 body, such partition being centrally perforated, a chambered plug seated in the cham-

ber in rear of the said partition having a forwardly extending part of reduced diameter, a miniature projectile carrying a sensitive detonating charge seated in the reduced 65 part of the said plug, a charge of powder for propelling the said projectile located in rear of said miniature projectile, a valve for closing gas-tight the passage through the aforesaid partition, the valve being arranged to 70 move to uncover the passage when the shell is fired, a movable valve carrier between the said plug and partition fitting tightly within the detonator body, a spring surrounding the reduced portion of the plug and acting upon 75 the movable valve carrier to normally hold the valve to its seat, and a plunger carrying a firing pin located in rear of the said plug arranged upon impact of the shell to ignite the charge of powder that propels the 80 miniature projectile, and means for causing detonation of the said miniature projectile when it arrives in proximity to the booster charge.

18. In a detonator for ordnance projectiles, a plunger carrying a firing pin and adapted to be set back when the projectile is discharged, bodies seated in the said plunger movable outward from the axis of the detonator under the influence of centrifugal force due to the rotation of the projectile, the said bodies carrying pins to engage with the walls of the detonator and hold the plunger retracted, the said pins being easily 90 frangible whereby they are sheared upon 95 impact of the projectile.

19. In a detonator for ordnance projectiles, a plunger operative in firing the primer of the detonator adapted to be set back when the projectile is discharged, and means, arranged to be brought into operation by centrifugal force due to the rotation of the projectile in flight for positively holding the plunger in a fixed set-back position with reference to its forward limit of movement, the 100 said means being frangible and arranged to be sheared or broken upon impact of the projectile.

20. In a detonator for ordnance projectiles, a plunger operative in firing the primer of the detonator, and means arranged to be brought into operation by centrifugal force due to the rotation of the projectile in flight for positively holding the plunger in a fixed 105 position back of its forward limit of movement, the said means being frangible and arranged to be broken upon impact of the projectile.

CHARLES P. WATSON.
